APPARATUS FOR RECOVERING CARBON BISULPHIDE AND SULPHURATED HYDROGEN DURING THE FINISHING PROCESS OF THE MANUFACTURE OF VISCOSE STAPLE FIBER

Waclaw Ufnowski, Warsaw, Poland; vested in the Alien Property Custodian

Application February 8, 1938, Serial No. 189,410
In Poland February 15, 1937

1 Claim. (Cl. 18—8)

In manufacturing staple fiber of the viscose type the material after having left the spinning machine and finished its coagulation, is treated by chemicals in form of different liquids. During these proceedings the band of threads either passes the successive baths without being cut or it is cut into staples beforehand and then the material is treated the same way.

The first of these processes quite generally is the treatment with hot water for removing the acid and at the same time the volatile substances as carbon bisulphide (CS_2) and sulphurated hydrogen (H_2S). The latter substances escape in gaseous form into the atmosphere and therefore the gas containing air is sucked off above the bath and sent into the open, to avoid expansion in the working room and poisoning the workers. This is of course partial help only, because the gases remain a nuisance for the surrounding area. But beside this, the valuable materials, namely CS_2 and H_2S are lost entirely.

Therefore it has been attempted to recover especially the carbon bisulphide by sealing off the treatment room as well as possible and sucking off the gases in a concentration as high as possible. But in this way one can only gain the gases in the form of a highly explosive mixture of gas and air, owing to the impossibility of exact tightening. Also liquefaction of the carbon bisulphide is hardly possible without losses.

The invention applied for avoids these disadvantages, making it possible, to get the gas under pressure and lead it away, without mixing it with air. This is achieved by closing off hydraulically the room in which the removing of acid and gases from the threaded material is executed. The material is fed and discharged continuously throughout the hydraulic closures in and from the chamber. To avoid premature gas development on the entrance of the material into the apparatus, this point is kept cool by an influx of cold water.

The apparatus for this proceeding will be described by means of the drawing. They are adapted to treat the material as a continuous band or cut into sections.

Figs. 1-3 and 4-6 show 2 forms of construction for the treatment of the material as band.

Figs. 7-8 and 9-10 show 2 forms of construction for the treatment of the cut material.

Fig. 1 is a cross section of Fig. 2 on line 2—2.

Fig. 2 is a cross section through Fig. 1.

Fig. 3 is a plan view of Figs. 1 and 2.

Fig. 4 is a cross-section of Fig. 5 on line 4—4.

Fig. 5 is a side view of Fig. 4.

Fig. 6 is a plan view of Fig. 4-5.

Figs. 7 and 9 are longitudinal sections in direction of the flow of material.

Figs. 8 and 10 are side views of Figs. 7 and 9 respectively.

In the construction according to Figs. 1-3 for treating the material as band, the apparatus consists of the two connected containers 17 and 14 with continuous cold water influx 11 through pipe 15 into container 17. The water is discharged through pipe 18 to overflow 19. Container 14 is fed with hot water through pipe 24. This entrance is provided above water-level 27 into a chamber 28. The latter is filled with Raschig-rings, balls or the like, through which the water runs into the treatment rooms. In counterflow the gases developed escape under pressure through chamber 28 and pipe 16 and in this way get washed with the hot water. If necessary the treatment room 14 may also be supplied with hot water or steam through the pipe 25 controlled by the valve 34. However, it preferably concerns an additional feeding of the room 14 while the main supply of hot water takes place through the pipe 24 in counterflow to the escaping gas.

The band of threads 13 runs continuously through pipe 15 over roller 20 through the container 17 and through the opening in the bottom of container 14 over the rollers 21 and 22, driven by the wheel 26, winds itself around them several times, being guided by means of the leading sticks 36, then passes through a second opening in the bottom of container 14 over guiding roller 23 and through pipe 18 for the next treatment.

Container 14 is fed with hot water in the manner already described or is heated by means of steam and so brought to the temperature customary for removing the acid and the volatile substances. The hot water, now containing acid

passes through the outlet hole for the band in the bottom of container 14 to container 17 and from here to the exterior as described. In this way the chamber 14 serves at the same time for removing acid and volatile substances as usual, so that the removing of gases if carried out in the manner described does not require any additional heat or hot water.

Figs. 4-6 show another form of the apparatus, which differs from the one described before only in the elimination of the rollers 20 and 23 as well as container 17.

The cylinders 21—22 may also be arranged side by side instead of vertically, furthermore it is possible to replace the cylinder 22 which is not

driven as well as the rollers 28, 23 by guiding sticks.

The apparatus for the continuous treatment of material already cut, designed in Figs. 7-8 and 9-10 are preferably a connection of two siphon-like containers, forming together a channel in form of the letter W. The material 18 goes continuously in uniform flow from the cutter or transporter into the entrance of the first siphon 15 in the direction of the arrow 19, under addition of cold water 11 for avoiding premature gas evolution. This emulsion or watery mixture of the material now gets into the second siphon 32, according to Figs. 7-8, under the influence of the level difference 28, 27 and from here under the influence of the level difference 27 I, 30 to the open for further treatment.

A further arrangement for the transport of the material through the apparatus is shown in Figs. 9-10. Here the transport is effected by means of the piston 31, moved up and down by the shafts 33 in direction of the arrow 35. The transport also may be effected by means of any other device as for instance transporting rollers (not shown).

The siphonlike channel is fitted with chambers 25 of which sloping openings or slits lead into the interior of the channel. Through these slits hot water or steam is supplied in direction of the flow of material and causes the heating up of the

emulsion or watery mixture to the temperature needed for removing the acid and volatile substances. Hot water is furthermore supplied in the manner already described through pipe 24 and chamber 28. The gases escape under pressure after having been washed as described above through chamber 28 and pipe 16. The room for removing of the acid and gases is shut off hydraulically and the continuous flow of the material is running through the hydraulic closures on the inlet and outlet of the room, so that the gases are gained under pressure in concentrated form and owing to the cooling of the entrance closure any premature gas development is avoided. The treated material after having left the apparatus is set free from water by sucking or squeezing off and conducted to further treatment.

I claim:

Apparatus for deacidifying and degassing artificial viscose fibers for recovering CS₂, H₂S and other gases in a continuous manner comprising a closed hot water filled chamber, hydraulically closed inlet and outlet means on said chamber for the fibers being treated, said means communicating with said chamber and a chamber on the top of and communicating with said first chamber, said last named chamber being provided with an inlet for hot water and an outlet for gas.

WACŁAW UFNOWSKI.
